UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,849**, dated September 2, 1873; application filed August 9, 1873.
[Term of Patent 3½ years.]

G.

To all whom it may concern:

Be it known that I, FREDERICK WINK, of Philadelphia, Pennsylvania, have invented a Design for a Shawl-Pattern, of which the following is a specification:

The main peculiarities of my design, which is clearly illustrated by the figure in the accompanying drawing, are the stripes *a* and *b*, which are of the same general character, both being ornamented by dots and bars, arranged in a manner too clearly shown in the drawing to need description.

The stripes *a* and *b* are members of the main stripe A of the pattern, which is otherwise

composed of a series of parallel plain stripes, bars, or ribs of varying widths, and of different shades or colors.

Irrespective of the colors employed, I claim—

1. The design for the stripe *a*, as shown and described.
2. The design for the whole pattern, as described and represented.

In testimony whereof I have signed my name to this specification in the presence of two subscribing witnesses.

Witnesses: FRED. WINK.

CLINTON M. LATOURETTE,
LEWIS T. GODFREY.
